UNITED STATES PATENT OFFICE.

ORPHEUS C. SHAW, OF SPOKANE, WASHINGTON, ASSIGNOR, BY DIRECT AND MESNE ASSIGNMENTS, TO THE MODERN THRESHING CYLINDER COMPANY, INC.

THRESHING-CYLINDER-TOOTH LOCK.

1,179,666.

Specification of Letters Patent. Patented Apr. 18, 1916.

Application filed October 28, 1915. Serial No. 58,387.

To all whom it may concern:

Be it known that I, ORPHEUS C. SHAW, a citizen of the United States, residing at Spokane, in the county of Spokane and 5 State of Washington, have invented certain new and useful Improvements in Threshing-Cylinder-Tooth Locks, of which the following is a specification.

This invention relates to improvements in 10 sectional cylinders for threshing machines and has to do more particularly with an improved means for locking a tooth bar against rotation under working thrust from the cylinder.

15 My invention consists in providing the cylinder ends with a plurality of head receiving recesses which are peripherally disposed in such a manner that the bars will be insertible and withdrawable peripherally of 20 the cylinder.

More particularly speaking, my invention relates to the novel formation of the recesses and in the provision of complementally formed heads whereby relative rotation of 25 the heads with respect to the cylinder will be prevented under working thrust of the cylinder.

My improved recesses are continuously smooth and unbroken both circumferentially 30 and transversely of their perimeters and they comprise releasing portions struck from relatively long radii centers and locking portions struck from relatively short radii centers so that the locking action will 35 be effected wholly by cam action and therefore increasing working thrust from the cylinder will serve to more firmly anchor the tooth bars against rotative movement.

A special object of my invention is to provide 40 a cylinder lock of this character which is of such configuration that the coating parts may be cast to shape so that the cylinder can be assembled without machining either the recess or the bar head, this object 45 being possible, in part, because of the omission of protuberant ribs on the bar head and corresponding cavities in the recess.

My invention will be more fully described in connection with the accompanying drawing 50 and will be more particularly pointed out in and by the appended claims.

In the drawing: Figure 1 is a view in end elevation of a threshing cylinder showing the same equipped with the device of my 55 invention. Fig. 2 is a view looking from

the right of Fig. 1. Fig. 3 is an enlarged view in end elevation of one of the recesses and one of the bar heads illustrating the manner in which the head is inserted. Fig. 4 is a similar view showing the head in- 60 inserted. Fig. 5 is a plan view of a tooth bar.

Like characters of reference designate similar parts throughout the different figures of the drawing.

As illustrated, 1 designates the cylinder 65 ends and 2 designates the intermediate member. Tooth bars are designated at 3 and the same are provided with teeth 4 which project radially, or substantially so, from the periphery of the cylinder, when the bars 70 are in place. Because of the staggered relation of the teeth I provide an intermediate member 2 having peripherally arranged offsets 5 whereby intermediate portions 6 may be locked thereto without interfering with 75 the staggered relation or disposition of the teeth, as will be seen more particularly by reference to Fig. 2.

I will next describe the particular formation of the locking recesses in the cylinder 80 ends and the locking heads formed on the tooth bars and by reason of the fact that all are identical in construction and operation I will only describe one in detail and I will use the term "cylinder end" as applying 85 either to the ends 1 or the intermediate member 2 and I will consider that the description of the heads at the ends of the tooth bars will be the equivalent to the intermediate members formed between the ends of the 90 bars. Generally speaking, the off-sets 5 have locking recesses 7 for receiving and retaining intermediate portions formed on the bars 3.

Now referring to Figs. 3 and 4, it will be 95 seen that the end 1 is provided with a recess extending radially inwardly from the periphery 8, and intersecting the latter. The recess is continuously smooth and unbroken both circumferentially and transversely of its perimeter. Said recess comprises a locking portion 9 which is struck from a center 10, and a releasing portion 11 which is struck from a center 12. The radius 13 is somewhat longer than the radius 14 but the locking portion 9 joins the releasing portion on a continuously curved line without any interruptions whatsoever. The tooth bar 3 is provided with a head 15 having a continuously smooth and unbroken periphery 110

shaped to correspond with the contour of the recess and comprising a locking portion 16, struck from a center 17 having a relatively short radius 18, and a releasing portion 19 struck from a center 20 and having a relatively long radius 21. When the head 15 is disposed in the manner shown in full lines, in Fig. 3, it may be inserted into the recess and when it is rotated or turned 10 as indicated in dotted lines, gradually toward the position shown in Fig. 4, the head will finally assume a position in which its entire periphery will be in engagement with the perimeter of the recess. Rotation of the cylinder will be in the direction indicated by the arrows in Figs. 1 and 4 and the working thrust will therefore tend to rotate the head 15 in the direction indicated by arrow X, rotation of the cylinder being indicated by 15 arrow Y and thrust on the teeth being indicated by arrow Z. Therefore, the locking portions 9 and 16 will coat structurally, to prevent rotation of the tooth bar relatively to the cylinder under working thrust.

20 25 I have now described how rotation under working thrust is prevented and I will next describe the manner in which longitudinal displacement is prevented. As will be seen more particularly by reference to Fig. 5, the tooth bar 3 has a cross-section which is 30 rectangular throughout the greater portion of its length and the heads 15 are formed on the bar at the ends of the latter, and likewise the intermediate portion 6, so that 35 shoulders 22 are formed at the ends, facing oppositely, and intermediate shoulders 23 are formed facing toward each other. The shoulders 22 engage the inside faces of the cylinder ends 1 while the shoulders 40 45 50 55 60 65 70 75 80 85 90 95 100 105 110 115 120 125 130 135 140 145 150 155 160 165 170 175 180 185 190 195 chored that rotary displacement under reversal will not occur.

55

It is believed that the advantages and utility of my invention will be fully understood from the foregoing description, and while I have herein shown and described one specific form of my invention, I do not wish to be limited thereto except for such limitations as the claims may import.

I claim:—

1. In combination, a threshing cylinder end, and a tooth bar, said cylinder end having a recess provided with a continuously smooth and unbroken perimeter circumferentially and transversely thereof, said recess having a releasing portion struck from a relatively long radius and a locking portion struck from a relatively short radius, said tooth bar having a head provided with a continuously smooth periphery circumferentially and transversely and said head being shaped to fit said recess and comprising a releasing portion struck from a relatively long radius center and a locking portion struck from a relatively short radius center whereby said bar will be locked against rotation in one direction when fitted in said recess, substantially as described.

2. In combination, a threshing cylinder having intermediate and end bar supporting portions provided with bar receiving recesses, and tooth bars having locking portions formed at their ends and between their ends for insertion into said receiving recesses, said locking portions being of different cross-section with respect to the cross-section of the remainder of said bars thereby forming shoulders on said bars for engagement with said supporting portions to prevent longitudinal displacement of said bars, substantially as described.

3. In combination, a threshing cylinder member and a tooth bar member, one of said members having a continuously smooth cam locking recess and the other of said members having a continuously smooth cam locking head complementally formed with respect to said recess to fit therein and prevent relative rotative movement between said members, substantially as described.

In testimony whereof I affix my signature.

ORPHEUS C. SHAW.
